5 Claims. (CL 123—170)

The invention relates to an internal combustion engine plant with at least two crankshafts driving a main shaft through a central gear and consists in that the gear member is provided with heating spaces connected to the cooling-circuit of the internal combustion engine, in order, by heating the gear member, to eliminate bending stresses in the transmission shafts which are supported partly in the gear member and partly in the internal combustion engine.

The heating spaces of the gear member and the cooling spaces of the internal combustion engine are connected in series in such a way that the heated cooling-water flows from the cooling-spaces of the engine into the heating spaces of the gear member. Cooling-water may also be withdrawn at an intermediate spot of the cooling-spaces of the internal combustion engine and led to the heating spaces of the gear member. In other cases a mixture of cooled water flowing to the engine and heated water flowing from the engine cooling-system can be led to the heating spaces of the gear member in order to be able to adjust the temperature of the gear member by varying the ratio of hot water to cold water. It is preferable to introduce the water below into the heating spaces of the gear member and to lead it away above from the heating spaces.

The invention is further explained with the help of the drawing, where Fig. 1 shows a side view and Fig. 2 a plan view of a simplified illustration of a construction according to the invention. The method of working of the object of the invention is explained with the help of Fig. 3 (longitudinal section) and Fig. 4 (front view).

The double-shaft opposed-piston engines 1 and 2 (Figs. 1 to 4) form an internal combustion engine set whose crankshafts 3 drive the main shaft 6 through the pinions 4 and the central gearwheel 5. The casing 7 of the gear has heating spaces 8 and 9 which are in connection with the cooling-medium circuit of the engines.

Through the pumps 10 and 11 (Figs. 1 and 2) the engines 1 and 2 and the cooler 12 receive cooling-water through the distributing piping 13. The heated cooling-water passes out of the collecting pipe 14 through pipe 15 into the lower part of the heating spaces 8 and 9 of the gear casing 7. The pipe 16 leads the water which has already passed through the heating spaces of the gear casing back again to the cooler 12. Between the recooled water in the distributing piping 13 and the heated water in the collecting pipe 14 there is only a small temperature difference, so

that the gear casing has practically the same temperature as the engine casing.

The transmission shafts are, as can be seen in Figs. 3 and 4, carried in the engine casing 1 or 2 and also in the gear casing 7. If the engine casing 1 or 2 expands when heated in the course of service, the transmission shafts will be liable to be subjected to bending stresses in the regions 17 between the engines and the gears. If the gear case 7 is heated in a suitable manner, the gear case also expands, so that bending of the transmission shafts between the engine and the gear at the regions 17 will be prevented and bending stresses cannot occur.

15 The cooling-water could for instance be taken from the cooler in two separate parallel circuits. One part of the cooling-water flows then into the cooling spaces of the engines and the other part into the heating spaces of the gear case. Since 20 there is only a small temperature difference between the recooled and the heated cooling-water, the gear case will assume practically the same temperature as the engine casing. Another possibility for leading in the cooling-water is that 25 water is taken from an intermediate spot of the engine cooling-spaces and led to the heating spaces of the gear case. The gear case then takes up practically the mean temperature of the engine casing. Also a mixture of cold water 30 flowing to the engine and hot water from the engine cooling system could be led to the heating spaces of the gear case, in order in this manner to be able to keep the gear case at the mean 35 temperature of the engine casing. Taking the cooling-water from an intermediate spot on the engines and the mixture of cold and hot water for heating the gear case is particularly recommended when water for cooling can be led to the engine cooling-spaces from a pipe, from a pond, 40 or from a lake.

The internal combustion engine according to the invention may also have only one or also more than two rows of cylinders. In the arrangement of several rows of cylinders the crank-45 shaft of each row of cylinders can drive the main shaft through the same central gear. Also more than one central gear could be provided for several rows of cylinders.

I claim:

50 1. Internal combustion engine plant with at least two crankshafts driving a main shaft through a central gear characterised in that the gear member is provided with heating spaces connected to the cooling-circuit of the internal combustion engine, in order, by heating the gear

member, to eliminate bending stresses in the transmission shafts which are supported partly in the gear member and partly in the internal combustion engine.

2. Internal combustion engine plant as claimed in claim 1, characterised in that the heating spaces of the gear member and the cooling-spaces of the internal combustion engine are connected in series in such a way that the heated cooling-water flows from the cooling spaces of the engine to the heating spaces of the gear member.

3. Internal combustion engine plant as claimed in claim 1, characterised in that cooling-water is withdrawn at an intermediate spot of the cooling-spaces of the internal combustion engine and led to the heating spaces of the gear member.

4. Internal combustion engine plant as claimed in claim 1, characterised in that a mixture of cooled water flowing to the engine and heated water flowing from the engine cooling-system is led to the heating spaces of the gear member, in order to be able to adjust the temperature of the gear member by varying the ratio of hot water to cold water.

5. Internal combustion engine plant as claimed in claim 1, characterised in that the water is introduced below into the heating spaces of the gear member and led away above from the heating spaces.

ERWIN WAEBER.
